UNITED STATES PATENT OFFICE.

GEORGE KELLY, OF MINERALPOINT, WISCONSIN.

COMPOSITE MATERIAL.

SPECIFICATION forming part of Letters Patent No. 696,343, dated March 25, 1902.

Application filed January 15, 1901. Serial No. 43,420. (No specimens.)

To all whom it may concern:

Be it known that I, GEORGE KELLY, a citizen of the United States, residing at Mineralpoint, in the county of Iowa and State of Wisconsin, have invented a new and useful Composite Material, of which the following is a specification.

My present invention relates to the production of what may be termed a "composite" material having soft spongy elastic properties and applicable for use in the manufacture of a wide variety of articles.

The object of the invention is to produce a composite material having a soft spongy self-sustaining structure throughout and having a facing or envelop of fibrous material held in place with great tenacity by a filler-core or substrata of matted burs, which by reason of their rough prickly character adhere with great tenacity to each other and to the vegetable or mineral fiber constituting the outer layer or facing of the material.

In the accompanying drawings, in which several embodiments of the invention are illustrated, Figure 1 is a perspective view of a mattress constructed in accordance with my invention and broken away at one corner to disclose the structure of the composite material. Fig. 2 is a detail sectional view, on a somewhat-enlarged scale, through a portion of the mattress illustrated in Fig. 1. Fig. 3 is a perspective view, with parts broken away, of a sheet of felt of composite structure. Fig. 4 is a perspective view of a tube, insulating-envelop, or pipe-covering. Fig. 5 is a perspective view of a fireproof insulating-sheet. Fig. 6 is a sectional view of a lubricating-wick or body of waste rendered self-sustaining in accordance with my invention. Fig. 7 is a similar view of a block or brick. Fig. 8 is a sectional view of a sheet applicable for use as a floor-deadener or for other purposes and comprehending compressed fibrous facings—as, for instance, paper—as distinguished from the loose fibrous layers illustrated in the preceding figures. Fig. 9 is a view of a cockle-bur.

In Figs. 1 and 2 I have illustrated a mattress 5, comprising the usual tufted covering 6 and a filler or stuffing of composite material produced in accordance with my present invention. The surface or outer layers of the

filler or stuffing comprehend sheets of loose but preferably closely-packed fiber—as, for instance, cotton and flax—constituting the 55 upper and lower layers 7 and 8, as shown, and united by an intermediate layer, core, or binder of matted burs, or, as shown in Fig. 2, two separate layers or mats of burs 9 and 10 may be employed with an intermediate 60 fibrous layer 11 of tow or the like.

The essential characteristic of the invention is the employment of a core, filler, binder, or substrata of burs in matted form, and it is essential to the accomplishment of my primary object that the burs employed be possessed of such great adhesive strength as to cling with great tenacity one to the other and to the fibrous material imposed upon the mat thus formed.

The bur which I have found to be most efficient for the formation of the adhesive mat or core is that known by the term "cockle." This bur is the rough prickly seed vessel or globular involucre of the burdock—a coarse 75 biennial weed heretofore considered valueless and distinguished from other burs by tentacles which are too flexible for protrusion through the fibrous layer and have hooked extremities which actually effect a positive engagement between contacting burs and also 80 positively engage the fibers imposed upon the mat. It will therefore appear that while burs other than cockle may be employed in some connections the cockle is best adapted for the 85 formation of the mat or core in the production of my composite material.

In constructing the mattress illustrated in Figs. 1 and 2 a mat of burs is first formed, and upon one side thereof is spread in any 90 suitable manner the sheet or layer of flax 8. The mat is then inverted, and upon its upper side is similarly imposed the layer 11 of tow fiber. Upon this in turn another layer or 95 mat of burs is imposed, and after the stuffing is completed by the imposition of the final layer 7 of cotton the covering is drawn to place and tufted in a manner well understood in the art.

In Fig. 3 I have illustrated a further embodiment of the invention—to wit, what may be termed a "flexible felt sheet" 12, comprising a mat 13 of cockle or other burs enveloped by a covering or envelop 14 of vegetable fiber.

These felt sheets may be rolled down, pressed, stitched, or otherwise supplementally treated to produce a sheet of flexible sheathing capable of being rolled up and well adapted for 5 the insulation of cars, cold-storage plants, or refrigerators where exceedingly - expensive insulations of hair felt are in general use.

In Fig. 4 I have illustrated a tubular envelop or pipe-covering formed from my composite material, the fibrous facings of which may be formed of vegetable fiber where the covering is intended for the insulation of cold pipes or may be mineral fiber—as, for instance, mineral wool, asbestos, and the like—15 if the covering is designed for the insulation of heated conduits or pipes.

In Fig. 5 I have illustrated a sheet of fire-proof felt comprising the cockle or other bur mat 13 and a fireproof envelop or facing 15 20 of mineral fiber.

Another connection in which the composite material may be employed to great advantage is in the production of lubricating material or waste wicks—such, for instance, as 25 are used by railroads for lubrication within the journal-boxes of cars. For this purpose flax fiber is being largely used, and sheep's wool is employed to some extent. Horsehair and sponge are generally considered as the 30 best lubricating materials, for the reason that both of them are durable, produce a proper feed of oil, and are sufficiently self-sustaining to remain for a long period in contact with the surface to be lubricated. This is also a 35 characteristic of flax fiber; but each of these materials, as well as sheep's wool, is expensive.

In Fig. 6 of the drawings I have shown in section a wad or wick for lubricating purposes, comprising the cockle core 16, which 40 is of spongy elastic formation and of insignificant cost and retains in self-sustaining form a covering 17 of any of the above-named materials, thereby greatly reducing the cost of the resulting wick by necessitating the employment of a comparatively small body of flax, wool, hair, or other fiber.

The bur mat or web, while it has a particular affinity for fibrous materials, is well adapted for use as a light spongy core for materials of other classes. For instance, in Fig. 50 7 I have shown a brick or block comprising a core 18 of burs and a covering or facing 19 of any suitable composition—as, for instance, plaster-of-paris, magnesia, or the like—which 55 may be molded around the prickly core to produce a cheap porous block. In this connection, as well as in others, a filler of any suitable material may be employed to fill up the interstices throughout the structure of 60 the mat or web; but in most cases this filler

will not be found necessary. The core is also well adapted for the retention of fibrous layers—as, for instance, paper—which have been reduced to an exceedingly compact body by pressure. A sheet of this character is illustrated in Fig. 8, in which 20 represents the cockle core or body, and 21 and 22 the paper facings. This sheet is well adapted for use as a carpet-felt or floor-deadener or may be made into large sheets and employed in building operations as a substitute for laths. When such use of the material is made, it would only be necessary to employ a few laths here and there to hold the material in place, the paper or felt facing constituting an excellent 75 plastering-surface and making it possible to dispense with the hair, which is now ordinarily employed with mortar in building.

I shall not undertake to enumerate all of the various uses to which this composite material may be put, because it is evident that it may be employed wherever a light body is desired or in the manufacture of any elastic mat, support, or cushion irrespective of the particular character or usefulness of the article. I therefore desire my invention to be understood, broadly, as residing in the utilization of matted burs as a substrata or binder for any character of imposed layer or facing which may be adhesively retained and supported by the mat, and in a somewhat more specific aspect the invention resides in the production of a composite material by combining with a mat, layer, core, or binder of burs a facing, covering, or envelop of fibrous 95 material, either vegetable, mineral, or any combination of vegetable or mineral fibers, or both.

What I claim is—

1. A composite material made up of a body 100 of matted burs, and a body of loose but closely-packed fiber in adhesive union therewith.

2. The combination with a composite material made up of a body of matted burs and 105 a body of loose but closely-packed fiber in adhesive union therewith, of a flexible cover inclosing the composite material thus formed.

3. A composite material made up of facings of loose but closely-packed fiber, and an 110 intermediate filler or core of matted burs in adhesive union with the fibrous facings.

In testimony that I claim the foregoing as my own I have hereto affixed my signature in the presence of two witnesses.

GEORGE KELLY.
